UNITED STATES PATENT OFFICE.

LOUIS E. GILES, OF NEW YORK, N. Y., ASSIGNOR TO UNDERWOOD COMPUTING MACHINE COMPANY, OF NEW YORK, N. Y., A CORPORATION OF NEW YORK.

COMPUTING-MACHINE.

1,370,429.

Specification of Letters Patent. Patented Mar. 1, 1921.

Application filed November 13, 1919, Serial No. 337,656. Renewed August 27, 1920. Serial No. 406,503.

To all whom it may concern:

Be it known that I, LOUIS E. GILES, a citizen of the United States, residing in New York, in the county of New York and State of New York, have invented certain new and useful Improvements in Computing-Machines, of which the following is a specification.

This invention relates to improvements in computing machines, and especially to machines capable of effecting algebraic computations, that is, of adding positive and negative numbers irrespective of their relative magnitudes, and of indicating the correct result, whether positive or negative.

The invention is herein disclosed as an improvement on the device illustrated and described in my prior application, Serial No. 331,585, filed October 18, 1919, which is, in turn, set forth as an improvement on a computing machine of the Underwood-Hanson type, such as the one illustrated and described in the Patent No. 1,278,812, granted September 10, 1918, to Hans Hanson.

As in the case of my prior invention, however, the present invention is adapted for use in connection with any computing machine having a register or totalizer comprising movable number wheels or other figure-carrying elements, and means for effecting either addition or subtraction by varying the positions of said figure-carrying elements.

In the form in which the invention is herein disclosed, as in my aforesaid improvement, I provide a duplicate set of figure-bearing elements or number wheels, corresponding in number and relative arrangement with the number wheels of the usual totalizer, and connect each wheel of the set, by means of an idler, with a corresponding totalizer number wheel. Also, as in the aforesaid prior improvement, I provide, for the added set of number wheels, a sight-opening of a width sufficient to expose two adjacent rows of figures. The number wheels of the added set are so geared or connected to those of the totalizer, and the sight-openings are so disposed relatively to said wheels that when a "0" of a totalizer number wheel is coincident with the totalizer sight-opening, a "0" and a "9" of the corresponding number wheel of the added set will be in register with the double-width sight-opening.

In my above-mentioned prior application, it was explained that the added set of number wheels and extra sight-opening afford means for indicating results of the opposite character to the character of the results ordinarily read from the usual sight-opening, the results of opposite character being read at the wide sight-opening, partly from one row of figures, and partly from the other.

As a means for facilitating the readings at the double-width sight-opening, my present invention includes a variably settable indexing device, herein disclosed as a shield or shutter, which, when set in a position having a readily determinable relation with respect to the figures exposed at the usual totalizer sight-opening, will conceal all figures of the two rows at the double-width sight-opening except those from which a reading is to be taken.

Although the double-width sight-opening has been herein disclosed in connection with the number wheels of the added set, it is within the scope of my invention to transpose the relative positions of the sight-openings in which case the double-width sight-opening would be associated with the usual totalizer number wheel, and the single-width sight-opening with the number wheels of the added set. Obviously, either sight-opening may be arbitrarily assigned as the one from which positive readings may be taken, the other being used in the reading of negative results.

From the foregoing brief description, it will be seen that the desired end is attained without the use of special carrying mechanism, mechanically-operated shutters, or other complicated mechanism, thus providing a very simple and practical device which will be inexpensive to produce, and not likely to get out of order and disable the machine, or cause it to give erroneous results.

Other features and advantages will hereinafter appear.

In the accompanying drawings,

Figure 1 is a top view of the front part of a computing machine of the Underwood-Hanson type, showing one embodiment of my invention as applied thereto.

Fig. 2 is a vertical section through the front part of the machine from front to rear, including an end view of the usual totalizer, the added set of number wheels

and the idlers by which the wheels of the added set are geared to the corresponding totalizer wheels, and a section through the reading gage or shutter.

5 Fig. 3 is a perspective view of the reading gage or shutter detached from other parts of the mechanism.

Figs. 4, 5 and 6 are views of the totalizer, illustrating different positions of the reading gage or shutter determinative of different readings.

As herein disclosed, the reference character 20 (Figs. 1 and 2) represents the front part of the casing of an Underwood-Hanson combined typewriting and computing machine, including the usual sight-opening 21, through which readings may be taken from the usual totalizer 22, comprising the usual number wheels 23 and rack-bars 24.

20 The usual tens-carrying mechanism for the totalizer and the mechanism for advancing the rack-bars, so as to operate the number wheels, is fully disclosed in the aforesaid Hanson patent, and the machine therein illustrated and described is in common use. The disclosure of the computing mechanism need not therefore be set forth in detail herein.

Geared to each of the number wheels 23, 30 by means of an idler 25, is a corresponding number wheel 26, of a secondary or subsidiary set of number wheels 27, the connection between said number wheels being such that each number wheel of the subsidiary 35 set will always rotate concomitantly with, and in exact accordance with, the corresponding number wheel of the totalizer 22. The subsidiary number wheels rotate in the same direction as those of the totalizer, and 40 each is provided, at its periphery, with a "0" and the digits "1" to "9", as usual, but the digits on the subsidiary number wheels are arranged in inverse order, as indicated diagrammatically in Fig. 2, by the figures 45 applied conventionally to the sides of said wheels.

Instead of the usual narrow sight-opening, there is provided in the machine casing 20 a sight-opening 28 for the subsidiary number wheels, said sight-opening being of a width sufficient to expose two adjacent 50 rows of the figures thereon.

When using a machine with my improvement applied thereto for ordinary arithmetical addition and subtraction, in which case the results are always positive, the readings 55 may invariably be taken from the totalizer number wheels, through the narrow sight-opening 21, as usual. But, should the machine be called upon to effect an algebraic computation, that is, if at any time the aggregate of the negative quantities added 60 exceeds the aggregate of the positive quantities, so as to result in an overdraft, or to 65 cause the machine to pass through "0", then

the readings may be taken from the subsidiary number wheels through the wide sight-opening 28 and will be read partly from one row of figures and partly from the other, the particular figures to be read from 70 the respective rows being determined by a reading gage or shutter 29, after properly setting the same in a manner hereinafter explained.

The reading gage 29 may be so mounted 75 as to slide between guide-plates 30 secured by rivets or other fastening devices 31 to the under side of the machine frame 20. The gage 29 may be provided with sight-openings 32, and 33, one in register with the 80 lower row of figures and the other in register with the upper row of figures of the two rows which register with the double-width sight-opening. The openings 32 and 33 extend in opposite direction from the 85 center of the gage, so as to be incapable of exposing two figures of the same denominational order at any one time. The gage may be provided with a finger-piece 34 by which it may be adjusted lengthwise to a reading 90 position determined by bringing an index 35 to a position which may be readily determined from inspection of the figures exposed at the sight-opening 21, as will be 95 hereinafter explained. The index 35 is so 100 positioned as to point to a figure of the upper row immediately over the left-hand figure exposed by the right-hand sight-opening of the reading gage.

When the machine has been cleared, in 100 readiness to commence a series of computations, the usual totalizer number wheels will exhibit a row of "0's at the narrow sight-opening 21, and the subsidiary number wheels will exhibit a row of "0's through 105 the sight-opening 33 of the reading gage 29, indicated in its normal position at the extreme left in Figs. 1 and 4. Starting with the machine in this condition, let it be assumed that the number 3,120,760 is to be 110 added to the number 876,421, and that the number 2,749,541 is to be subtracted therefrom. As the numbers are successively set up on the keyboard and run into the totalizer they will be accumulated and the successive results will appear at the upper or narrow sight-opening 21, the arithmetical total of the three numbers being the positive quantity 1,247,640, as indicated, (Fig. 4).

Should the machine now be operated in 120 an attempt to subtract the number 2,109,614 from that previously accumulated in the totalizer, the correct algebraic sum, which should be -861,974, would not appear in the row of figures exposed at the upper 125 sight-opening as before, but, instead of this result, there would appear, as indicated in Fig. 5, a complementary series of figures 999,138,026, which, if added to the correct result, ignoring the minus sign, would be 130

represented by a "1" followed by as many "0's as there are denominational orders or decimal places in the totalizer. It is well known to those skilled in the art that this will happen whenever the number to be added is larger than that previously accumulated in the totalizer and of opposite character, as when a negative number is added to a smaller positive number.

- 10 It may be observed that the first figure at the upper sight-opening, after the last-mentioned algebraic computation has been effected (see Fig. 5), is a "9" instead of the usual "0", and this will always be true when 15 a negative number has been added to a smaller positive number previously accumulated in the totalizer, provided the machine is not used to add or subtract numbers having as many digits as there are number 20 wheels in the totalizer. In using a machine with my invention applied thereto, I therefore arbitrarily select one having at least one more number wheel in its totalizer than the number of digits of the largest number 25 which it is intended to be capable of adding or subtracting, and assign the highest number wheel to a special purpose, that is, for use as a signal or warning, to indicate whether the result is positive or negative. 30 Under such circumstances, the highest number wheel of the totalizer will normally expose a "0" at the narrow sight-opening 21. This "0" can never be changed to "9" by adding positive numbers, except as a result 35 of a large number of successive computing operations, and in no event could it be changed from "0" to "9" by adding positive numbers, except by being first caused to exhibit all of the digits "1", "2", "3", etc., 40 in succession up to "9". It is well known, however, that the highest number wheel will be invariably caused to immediately expose "9" whenever any negative number is added to a smaller positive number previously 45 accumulated in the totalizer, so as to result in an overdraft and cause the machine to pass through "0". The appearance of the "9" on the highest number wheel at the upper or narrow sight-opening 21 50 may, therefore, serve as a warning or signal to the operative that the result indicated by the totalizer is negative, in which case the correct result may be obtained by setting the reading gage 29 in a manner which will now 55 be described, and then reading the figures exposed at the sight-openings 32 and 33.

Referring again to Fig. 5, it may be observed that the last figure exposed at the upper or narrow sight-opening 21 is a significant figure, that is, a digit rather than a "0". Whenever this is found to be the case, the operative should slide the reading gage to the right until the index 35 is in register with the last-mentioned digit, "6" 60 in the example illustrated, after which the

correct negative reading -861,974 will appear at the sight-openings 32 and 33, as indicated at Fig. 5, all except the last figure being taken from the lower row. After making the reading, the operative should 70 restore the reading gage to its normal position to the left.

Should the machine now be operated in an attempt to add to the sum already accumulated in the totalizer another negative quantity, as for example, -4,836,026, it will be found that the "9" is still exhibited by the highest totalizer number wheel at the sight-opening 21, indicating that the result is again negative in character (see Fig. 80 85 6). It may also be observed that the last significant figure exposed at the sight-opening 21 is now in thousands place, all to the right of the "2" of that denomination being "0's. Under such circumstances, the 85 operative should move the reading gage until the index 35 is in register with the "2" in thousands place, after which the correct result -5,698,000 may be taken from the sight-openings 32 and 33 (Fig. 6) as before, the figures 569 appearing at the lower left-hand opening 32, and the figures 8,000 at the upper right-hand opening 33.

The rule suggested by the above illustrative examples is invariable. So long as a "0" is exhibited by the highest number wheel of the totalizer, the result is positive and should be read from the upper sight-opening 21 in the usual manner. Whenever a "9" is exhibited by the highest number wheel at the sight-opening 21, the result is negative. The operative may then, by merely sliding the reading gage toward the right until the index 35 is in register with the last significant figure exhibited at the sight-opening 21, take the negative reading from the sight-openings 32 and 33 of the reading gage, which will conceal all figures in register with the double-width sight-opening except those from which the reading is 110 to be taken.

The above-stated rule is simple and invariable in its application, and could be readily mastered by an operative in a negligible space of time, after which the negative readings may be taken from the machine with the same degree of ease and accuracy as in reading the positive results in an ordinary totalizer.

It will be obvious that the double-width sight-opening and reading gage may be used in connection with either set of number wheels, and that either set of figures may be used to exhibit positive results, the other being used to exhibit negative results.

If desired, the figures on the subsidiary number wheels may be differentiated from those of the totalizer itself, as by making those of the totalizer black, to indicate positive results, and those of the sub-

sidiary set red, to indicate negative results. This, however, is in no manner necessary, since the difference in location and width of the sight-openings may be relied upon 5 as a means for determining from which number wheels results of either character are to be taken.

Any appropriate means may be substituted for the idlers for causing corresponding 10 wheels of the two sets to be concomitantly rotated. In the form herein disclosed, the number wheels of the respective sets rotate in the same direction, and the figures on one set are duplicates of those on 15 the other, except that they are arranged in inverse increasing order of magnitude, that is, rotation, such as to expose figures on one wheel in increasing order of magnitude, causes those of the other to be exposed in decreasing order of magnitude. Should the 20 wheels be so geared or connected as to rotate in opposite directions, the figures should be applied to the number wheels in the same relative order, so as to be brought to the 25 sight-openings in the inverse order explained above.

Any appropriate form of indexing device may be used which includes means for positioning the same in its proper position relative 30 to the last significant figure exposed at the narrow sight-opening, and which has means for selectively directing attention to the figures of the two rows from which a reading is to be taken at the double-width 35 sight-opening.

Variations may be resorted to within the scope of the invention, and portions of the improvements may be used without others.

Having thus described my invention, I 40 claim:

1. In an algebraic computing machine, in combination, a set of number wheels having figures by which positive results may be represented, a second set of number wheels having figures by which negative results may be represented, means for causing each wheel of the second set to rotate concomitantly with the corresponding wheel of the first set, and indexing means for directing attention to one row of figures on the wheels of one of said sets from which a reading of one character may be taken, and for directing attention to figures of two adjacent rows on the wheels of the other set from which a 55 reading of the opposite character may be taken, said indexing means including a reading gage settable in a position such as to selectively direct attention to the particular figures of the two adjacent rows by which a 60 number to be read is represented.

2. In an algebraic computing machine, in combination, a set of number wheels having figures by which positive results may be represented, a second set of number wheels having figures by which negative results 65

may be represented, means for causing each wheel of the second set to rotate concomitantly with the corresponding wheel of the first set, and indexing means for directing attention to one row of figures on the wheels 70 of one of said sets from which a reading of one character may be taken, and for directing attention to figures of two adjacent rows on the wheels of the other set from which a reading of the opposite character may be taken, said indexing means including a variably settable reading gage having open portions for selectively exposing, when set, the particular figures of the two adjacent rows by which a number to be read is represented, 75 and having portions for concealing the remaining figures of both of said rows.

3. In an algebraic computing machine, in combination, a set of number wheels having figures by which positive results may be represented, indexing means for directing attention to one row of said figures from which a reading may be taken, a second set of number wheels having figures by which negative results may be represented, means 80 for causing each wheel of the second set to rotate concomitantly with the corresponding wheel of the first set, and indexing means for concomitantly directing attention to figures of two adjacent rows on the wheels 85 of the second set from which a reading may be taken, said last-mentioned indexing means including a reading gage settable in a position such as to selectively direct attention to the particular figures of the two adjacent rows by which a number to be read is 90 represented.

4. In an algebraic computing machine, in combination, a set of number wheels having figures by which positive results may be represented, indexing means for directing attention to one row of said figures from which a reading may be taken, a second set of number wheels having figures by which negative results may be represented, means for causing each wheel of the second set to rotate concomitantly with the corresponding wheel of the first set, and indexing means for concomitantly directing attention to figures of two adjacent rows on the wheels of the second set from which a reading may be taken, said last-mentioned indexing means including a variably settable reading gage having open portions for selectively exposing, when set, the particular figures of the two adjacent rows by which a number to be read is represented, and having portions for concealing the remaining figures of both of said rows.

5. In an algebraic computing machine, in combination, a set of number wheels having figures by which positive results may be represented, a second set of number wheels having figures by which negative results may be represented, means for causing each 125

- wheel of the second set to rotate concomitantly with the corresponding wheel of the first set, a fixed index having a sight-opening for exposing one row only of the figures 5 on the wheels of one of said sets, and a variably positionable index having sight-openings for selectively exposing figures of two adjacent rows on the wheels of the other of said sets by which a number to be read is 10 represented, and having closed portions for concealing all other figures of both of said rows.
6. In a computing machine, in combination, a set of number wheels having figures 15 by which positive results may be represented, an index for said wheels comprising a sight-opening for exposing one row only of the figures thereon, a second set of number wheels having figures by which negative results may be represented, means for causing each wheel of the second set to rotate concomitantly with the corresponding wheel of the first set, and a variably settable index for the wheels of said second set having 20 sight-openings for selectively exposing figures of two adjacent rows thereon by which a number to be read is represented, and having closed portions for concealing all other figures of both of said rows.
7. In a computing machine, in combination, a totalizer having two sets of number wheels, each having figures comprising a "0" and the digits "1" to "9", indexing means for directing attention to one row of 25 figures on the wheels of one of said sets, and indexing means for directing attention to figures of two adjacent rows on the wheels of the other of said sets, said second-mentioned indexing means comprising a movable reading gage having openings for selectively exposing the particular figures of the two adjacent rows by which a number to be read is represented to the exclusion of others.
8. In a computing machine, in combination, a totalizer having two sets of number wheels, each having figures comprising a "0" and the digits "1" to "9", an index for directing attention to one row only of the 30 figures on the wheels of one of said sets, and a variably settable index for selectively directing attention to one or more figures of one row, and to other figures of an adjacent row on the wheels of the other set.
9. In a computing machine, in combina- 35
- tion, a totalizer having two sets of number wheels, each having figures comprising a "0" and the digits "1" to "9", indexing means for directing attention to one row only of the figures on the wheels of one of said sets, and indexing means for directing attention to figures of two adjacent rows on the wheels of the other of said sets, said second-mentioned indexing means comprising a movable reading gage having openings out of alignment with each other and extending in opposite directions from a center line for selectively exposing the particular figures of the two adjacent rows by which a number to be read is represented, said reading gage 40 also having a projecting index pointer in line with the inner end portion of the right-hand opening and capable of being moved during a setting of said gage along the single row of figures to a point determinative of a reading position.
10. In a computing machine, in combination, a set of number wheels having figures thereon, a sight-opening of a width sufficient to expose two adjacent rows of said figures, 45 and a variably movable reading gage having two openings, each of a width sufficient to expose one row only of said figures, said openings being respectively in registration with the two adjacent rows of figures on said wheels which are in register with said double-width sight-opening and extending in opposite directions from a center line.
11. A reading gage for a computing machine, said gage having two sight-openings, 50 each of a width sufficient to expose but one row of figures, said openings being out of alignment and extending in opposite directions from the center of the gage.
12. A reading gage for a computing machine, said gage having two sight-openings, 55 each of a width sufficient to expose but one row of figures, said openings being out of alignment and extending in opposite directions from the center of the gage, said gage also having a projecting index element in line with the left end portion of the right-hand sight-opening by means of which said gage may be positioned for the taking of a reading.
